UNITED STATES PATENT OFFICE.

SAMPSON WEINSHENK, OF CHICAGO, ILLINOIS.

MATTRESS.

1,418,501.

Specification of Letters Patent. Patented June 6, 1922.

Application filed May 21, 1920. Serial No. 383,087.

To all whom it may concern:

Be it known that I, SAMPSON WEINSHENK, a citizen of the United States, and a resident of the city of Chicago, in the county of Cook and State of Illinois, have invented certain new and useful Improvements in a Mattress; and I do hereby declare that the following is a full, clear, and exact description of the same, reference being had 10 to the accompanying drawings, and to the numerals of reference marked thereon, which form a part of this specification.

This invention relates to a mattress, and more particularly a type of mattress which 15 is especially adapted for use by military organizations and by campers and tourists.

The practice heretofore has been to either omit the mattress altogether and sleep on blankets on the ground, or to carry a separate mattress when transportation facilities made it possible. Disadvantages resulted from each of these arrangements in that when the mattress was omitted, the sleepers were obliged to undergo considerable 25 discomfort, and when a separate mattress was carried the inconvenience of arranging covering thereon had to be contended with. It was also necessary to carry a separate pillow which often became separated from the rest of the bedding and which was inconvenient to pack.

The familiar type of sleeping bag has failed to overcome these disadvantages in that it is not readily accessible for cleaning 35 and that it does not provide a good cushion between the wearer and the ground.

It is an object, therefore, of this invention to provide a mattress which is adapted to be compactly folded and readily accessible 40 for cleaning and which has pillow and covering portions permanently associated therewith.

It is also an object of this invention to provide a mattress comprising inflated cushioning portions permanently joined together by flexible hinge sections and having flexible covering means secured thereon.

It is an important object of this invention to provide a mattress having pillow and 50 cover sections hinged thereon.

Other and further important objects of this invention will be apparent from the disclosures in the specification and the accompanying drawings.

The invention (in a preferred form) is 55 shown on the drawings and hereinafter more fully described.

On the drawings:

Figure 1 is a plan view of the mattress of this invention with the cover and pillow 60 sections opened out for cleaning or airing.

Figure 2 is a plan view of the mattress of this invention showing the pillow and cover sections thereof in position for use.

Figure 3 is a side elevation of the mattress showing the pillow and cover sections in position for use.

Figure 4 is a section on line 4—4 of Figure 2.

Figure 5 is a section on line 5—5 of Figure 2.

Figure 6 is a side elevation of the mattress folded for packing or transportation.

Figure 7 is an end elevation of the folded mattress.

Figure 8 is a side elevation of a modified form of mattress embodying the principles of this invention.

Figure 9 is a section on line 9—9 of Figure 8.

Figure 10 is a section on line 10—10 of Figure 9.

Figure 11 is a side elevation of the modified form of mattress folded for packing.

As shown on the drawings:

The bottom or cushioning portion of the mattress of this invention may conveniently comprise connected sections 1, 2 and 3 and to said bottom portion is hinged a head rest or pillow 4 by means of a flexible strip 5 90 which is conveniently of the same material as the covering used for said sections 1, 2 and 3, and a covering portion 6, which is ordinarily made of greater width than the bottom or cushioning portion and which is 95 hinged to said portion by the flexible portion 7. Said bottom sections 1, 2 and 3 and the pillow 4 are conveniently stuffed with a padding material 8, which may, if desired, be quilted therein and comprises any suitable padding material such as cotton felt, sea moss, etc. Padding material 8 may also be placed in the cover portion 6 and serves to add to the warmth afforded by said cover portion without materially increasing the 100 total weight of the mattress.

It is of course to be understood that the bottom portion may be made continuous

instead of in sections 1, 2 and 3, as shown, and that various methods of hinging the cover and pillow sections thereon may be employed.

5 As shown, it is also desirable to provide a reenforcing covering 9 for the under side of the bottom portion of the mattress, in order to prevent dampness from the ground from penetrating the mattress. This reenforcing covering 9 may, of course, be made of water-proof material if desired.

A mattress of the type shown in Figures 1 to 7 inclusive may conveniently be constructed with integral portions of covering 15 material between which cushioning material 8 may be provided as desired, and the flexible hinged portions 5 and 7 are formed by merely stitching together said top and bottom covering portions without any cushioning material therebetween.

The modified mattress of this invention, which is shown in Figures 8 to 11 inclusive, is designed to afford the advantages hereinbefore described, and is also adapted to be 25 packed in a very small space which makes it particularly desirable for tourist use.

As shown in Figures 8 and 10, the bottom of said modified form of mattress comprises inflatable sections 10, 11 and 12, to which an 30 inflatable pillow is hinged by means of a flexible strip 14, and a cover section 15, which is ordinarily of greater width than the inflatable sections 10, 11 and 12, and which is hinged thereon by flexible means 17. Said cover section 15 may of course be 35 quilted or padded or comprise suitable fabric as desired. Valves 16 are provided whereby air may be introduced into the sections 10, 11 and 12 and into the pillow 13 40 to inflate the same and whereby the air may be allowed to escape from said sections when it is desired to deflate them for packing. When this form of mattress is deflated it may, of course, be packed in a very small 45 space, since the sections 10, 11 and 12 may be completely collapsed and the mattress folded as shown in Figure 11.

Since the inflated portions of the mattress shown in Figures 8 to 11 inclusive are provided with means whereby they may be separately inflated, it is possible for the user of the mattress to inflate these sections individually to the desired degree, an arrangement which adds materially to the 5 comfort of the user.

As is apparent from the foregoing description, the mattress of this invention provides in reality a complete bed, which may be readily transported and all parts of

which are easily accessible for cleaning. Troubles due to lost pillows or blankets are avoided, and since the improved mattress need only be unrolled to have a complete bed in readiness, a considerable saving of time is effected.

60 The mattress of this invention is also desirable in permanent camps or other institutions where transient visitors often arrive at late hours and have not provided themselves with blankets or other covering.

65 70 I am aware that changes of construction may be varied through a wide range without departing from the principles of this invention, and I therefore do not purpose limiting the patent granted otherwise than 75 necessitated by the prior art.

I claim as my invention:

1. In a device of the class described, a mattress comprising several sections, hinge connections between said sections, the width 80 of each hinge connection being less than half the thickness of the mattress, a pillow, a hinge connection between said pillow and the mattress, the width of said hinge connection being more than half the thickness of the 85 mattress, a cover for the mattress, a hinge connection between the mattress and said cover, the width of said connection being greater than half the thickness of the mattress, a water-proof reinforcement secured 90 to one face of the mattress and a reinforcement secured to that face of the cover which when the device is unfolded is on the same side as the reinforcement of the mattress, the width of the cover being greater than the 95 width of the mattress.

2. In a device of the class described, a mattress comprising several sections, hinged connections between said sections, the width of each hinge connection being less than 100 half the thickness of the mattress, a pillow, a hinge connection between said pillow and the mattress, the width of said hinge connection being more than half the thickness of the mattress, a cover for the mattress, a hinge 105 connection between the mattress and said cover, the width of said connection being greater than half the thickness of the mattress, the width of the cover being greater than the width of the mattress.

110 In testimony whereof I have hereunto subscribed my name in the presence of two subscribing witnesses.

SAMPSON WEINSHENK.
